(57) **CLAIM**

An ornamental design for a valve cap adapter, as shown and described.

DESCRIPTION

FIG. 1 is an isometric view showing the top of our design of a valve cap adapter.

FIG. 2 is a front elevational view of the valve cap adapter of FIG. 1.

FIG. 3 is a rear elevational view of the valve cap adapter of FIGS. 1 and 2.

FIG. 4 is a left side elevational view of the valve cap adapter of FIGS. 1-3.

FIG. 5 is a right side elevational view of the valve cap adapter of FIGS. 1-4.

FIG. 6 is a top plan view of the valve cap adapter of FIGS. 1-5.

FIG. 7 is a bottom view of the valve cap adapter of FIGS. 1-6.

FIG. 8 is an isometric view showing the top of a second embodiment of our design of a valve cap adapter.

FIG. 9 is a front elevational view of the valve cap adapter of FIG. 8.

FIG. 10 is a rear elevational view of the valve cap adapter of FIGS. 8 and 9.

FIG. 11 is a left side elevational view of the valve cap adapter of FIGS. 8-10.

FIG. 12 is a right side elevational view of the valve cap adapter of FIGS. 8-11.

FIG. 13 is a top plan view of the valve cap adapter of FIGS. 8-12; and,

FIG. 14 is a bottom view of the valve cap adapter of FIGS. 8-13.

The broken lines of FIGS. 1-14 are for the purpose of illustrating portions of the article in which the design is embodied that form no part of the claimed design.
